REAMER

Stuart A. Cogsdill, Detroit, Mich., assignor to
 Cogsdill Twist Drill Company, Inc., Detroit,
 Mich., a corporation of Michigan

Application February 28, 1938, Serial No. 193,155

2 Claims. (Cl. 77—75.5)

The invention relates to cutting tools and refers more particularly to expansion reamers.

The invention has for one of its objects to provide an expansion cutter in which the cutting blades may be readily adjusted. The invention has for other objects to provide an improved adjustment means and to so construct the adjustment means and the expansion cutter that the adjustment means cooperates with the radially movable parts of the expansion cutter to form in effect a continuous annulus whereby force to which one part may be subjected is distributed to the other parts. The invention has for a further object to provide a simple construction of expansion cutter which may be manufactured at relatively low cost.

With these and other objects in view, the invention resides in the novel features of construction and combinations and arrangements of parts as more fully hereinafter set forth.

In the drawing:

Figure 1 is an end elevation of a cutting tool showing an embodiment of my invention;

Figure 2 is a cross section on the line 2—2 of Figure 1;

Figure 3 is a cross section on the line 3—3 of Figure 2;

Figure 4 is a side elevation of a portion of Figure 2;

Figure 5 is a perspective view of the adjustment device.

As illustrated in the present instance, my invention is embodied in an expansion reamer in which 1 is the body having the shank 2 at one end and the expandable portion 3 at the other end. The expandable portion comprises the annular series of circumferentially separated flexible resilient longitudinal tongues 4 integral with the body and constituting parts adapted to be moved generally radially.

While the blades may be formed integral with the tongues, they are preferably formed separately and of high speed steel, while the body is preferably formed of nickel steel. Each of the tongues 4 is preferably provided with the pair of generally longitudinally extending slots 5 which are symmetrically disposed with respect to the longitudinal median plane of the tongue. 6 are the blades engageable in the slots. Each of the blades is preferably provided with the plurality of recesses or notches 9 in its side terminating in the cutting edge, which recesses are filled by integral portions of the tongues, whereby the blades are permanently secured to the tongues. In forming the reamer, the slots 5 are

cut in an end portion of the body 1 and the blades 6 are formed with the recesses or notches 9 in their sides. These recesses or notches may be formed as shown, or have other shapes, or may be provided by a knurling operation. After the 5 blades have been inserted into the slots, the portions of the body adjacent the sides of the blades having the recesses or notches are subjected to a forging operation which displaces the body to provide the portions extending into and filling the 10 recesses or notches. Then the body is longitudinally severed or slit to form the tongues 4.

For the purpose of expanding the reamer, I have provided the expanding device 10 which is adapted to exert a circumferential force upon the 15 tongues to move the blades generally radially. This adjustment device comprises the screw 11 which extends axially of the body and has the shank 12 which clears the tongues 4 and threadedly engages the portion of the shank 2 in the 20 zone adjacent the expandable portion 3. This screw is provided with the head 13 which preferably flares outwardly from the shank. 14 is a wedge member rotatably mounted upon the screw 11 and held from disengagement therefrom 25 by the head 13 and suitable means, such as the pin 15, extending transversely through the shank 12. The wedge member 14 has the hub portion or collar 16 of an external diameter such that it may be inserted within the bore formed by the 30 tongues 4. This wedge member also has extending radially from its hub portion the wedge elements 17, the number of these elements corresponding to the number of slits between the tongues. Each wedge element is wedge-shaped 35 in an axial direction and flares axially outwardly. Furthermore, the outer portions of the side edges of the tongues are preferably flared axially outwardly to cooperate with the wedge elements as the latter are moved axially inwardly. The head 40 of the screw is preferably provided with the polygonal-shaped socket 18 for engagement by a suitable tool by means of which the screw may be threaded into the body to thereby move the wedge member axially inwardly to expand the 45 expandable portion of the reamer.

The construction is such that the wedge member through its wedge elements is adapted to exert a circumferential force upon the tongues to move these tongues away from each other to 50 thereby move the blades carried by the tongues generally radially outwardly. The wedge elements being located between the tongues cooperate with these tongues to form a continuous annulus so that force to which one tongue is sub- 55

jected through its blade is distributed to the other tongues. As a result, the adjustment device functions to provide a reinforced rigid construction of expansible reamer when in use whereby the blades are effectively held in their various positions of adjustment from vibrating.

What I claim as my invention is:

1. In a cutting tool, a body having an annular series of resilient longitudinal tongues, blades upon said tongues, a collar having wedge elements adapted to extend between and engage adjacent tongues, and a threaded member engaging said collar and adjustable to adjust said collar axially of said body.

2. In a cutting tool, a body having an annular series of resilient tongues each formed with a generally longitudinally extending slot, of blades extending within said slots, each blade being formed in one of its sides with a recess, said tongues having deformed portions extending into and substantially filling the recesses to lock said blades to said tongues, and means internally engageable with said tongues for moving the same in a generally radial direction.
